UNITED STATES PATENT OFFICE

1,995,235

CUTTING BIT FOR MINING MACHINES

John H. Wenzlick, Wheeling, W. Va., assignor
to Warwood Tool Company, Wheeling, W. Va.,
a corporation of West Virginia

Original application July 18, 1932, Serial No.
623,211. Divided and this application Sep-
tember 21, 1933, Serial No. 690,481

1 Claim. (Cl. 266—33)

The invention relates to new and useful im-
provements in cutting bits for mining machines.

An object of the invention is to provide a cut-
ting bit for mining machines wherein the grain
5 of the stock in the finished bit is in layers parallel
with the cutting face of the bit so as to prevent
splitting of the metal under cutting strains
thereon.

A further object of the invention is to provide
10 mining bits of the above character which are
joined in pairs by an integral web of metal that
is readily fracturable when it is desired to put the
bit in use and wherein the connecting web of
metal is the resultant action of the forming and
15 shaping of the cutting ends of the bits.

In the drawing, which shows by way of illus-
tration one embodiment of the invention,

Figure 1 is a side view of a mining bit embody-
ing the improvements and showing in broken
20 lines the grain of the metal forming the bit.

Figure 2 is a perspective view of the finished
mining bit.

Figure 3 is a sectional view in line 3—3 of
Fig. 2.

25 Figure 4 is a section of bar stock from which
a pair of mining bits are made embodying the im-
provements.

Figure 5 shows the first step in bending the
metal so as to provide inclined cutting faces of
30 the bits with the grain of the metal parallel there-
with.

Figure 6 is a view showing the blank after
the cutting ends of the bits have been shaped
by swaging action thereon.

35 Figure 7 is a plan view of the same.

The construction of the mining bit embodying
my improvements will probably be better under-
stood by the method of making the same. The
bit for mining machines embodying the improve-
40 ments consists of a shank or body portion 1 which
is longitudinal in cross-section. Said body por-
tion is offset so as to provide a connecting end 2
having a lip face 3 leading to a cutting point 4.
This lip face 3 inclines upwardly and away from
45 the upper edge face 5 of the body portion. The
cutting end of the bit is also provided with a
clearance face 6 leading from the point 4 to the
under edge face 7 of the body portion. This
clearance face 6 inclines inwardly away from
50 the cutting point so that the cutting point 4 over-
hangs said clearance space 6. The grain of the
metal forming my improved mining bit is parallel
with the edge portions 5 and 7 of the shank or
body portion of the bit. It is also parallel with
55 the inclined lip face 3 of the bit. The grain of

the metal is indicated by the broken lines in Fig.
1. The lip face 3 of the cutting bit is preferably
flat and lies in a plane containing the curved
edges 3, 8 of said cutting end.

It is thought that the structure of the mining
bit will be better understood by a description of
the method by which it is made, for it is very
essential that in the finished bit the grain of
the metal shall be substantially parallel with the
5 lip face of the bit. When the grain is parallel
with the lip face, in effect the metal lies in layers
one upon the other and the cutting strains im-
posed upon the cutting face of the bit approach a
right angle strain to the plane of the grain.
This prevents any splitting of the metal along
10 the grain when said bit is subjected to the cutting
strains.

In Fig. 4 of the drawing, there is shown a sec-
tion of bar stock at 9 which is rectangular in
cross-section. This bar stock is of suitable steel
20 for producing a cutting tool which may be used
for cutting clay, coal, stone and the like. The bar
stock is subjected to die pressure for offsetting
the section 9a relative to the section 9b. Inter-
mediate these sections the metal is bodily dis-
placed without disturbing the grain of the metal.
25 In other words, the grain of the metal is sub-
stantially parallel with the line x—x of Fig. 5
which lies parallel to the upper and lower faces
of the bar stock after it has been offset to pro-
vide the connecting portion 9c. This central
30 section 9c is utilized for forming the cutting ends
of two bits which are in reverse position so that
the one edge portion of this intermediate sec-
tion will form the cutting lip face of one bit,
35 while the other edge portion of this intermediate
section will form the cutting lip face of the other
bit. The blank is then subjected to die pressure
for shaping the side faces of the cutting ends
of the two bits and also for shaping, if desired,
40 the lip faces of the two bits so that they will
be substantially flat although inclined relative
to the edge face of the body portion into which
these lip faces merge. During this shaping of
the two bit faces by die pressure, the metal is
45 reduced to a thin web along the line y—y (Fig.
6). This connecting web is indicated at 10 in
the drawing. The two bits are in finished con-
dition so that if the metal be fractured along
this line y—y, or at this thin web 10, then the
50 two bits will be in finished condition ready for
use.

It is noted that when one section of the bar
stock is offset relative to the other, so as to

provide this intermediate section which is then shaped into the cutting ends for the two bits, the grain of the stock remains parallel with the side edges throughout this section which is to be shaped into said cutting ends. Therefore, in the finished bits, the grain of the stock is substantially parallel with the cutting lip face 3 of each bit. It is this laying of the grain of the stock relative to the cutting face that constitutes the essentially new feature in the cutting bit. Applicant has also produced a new article in the two bits which are joined together by a thin web of metal along their clearance faces, which web can be readily ruptured so as to render the same ready for use. The connecting web is an incident in the method of making the bits and it serves as a bond for the two bits so that they may be handled and stored as a unit in pairs.

20 The method of forming the bits as described

above is described in greater detail and claimed in my copending application Serial No. 623,211, filed July 18, 1932, and of which application this present application is a division.

Having thus described the invention, what I claim as new and desire to secure by Letters Patent, is:

As an article of manufacture, a coal mining machine cutting bit comprising a single homogeneous piece of metal providing a shank terminating in a cutting end offset from the shank to provide a cutting lip face inclining upwardly away from the upper longitudinal face of the shank, and wherein the grain of the metal in said cutting end is parallel to said inclined face, said cutting end having an inclined clearance face extending inwardly from the cutting point of the lip face to the lower longitudinal face of the body portion.

JOHN H. WENZLICK.
